United States Patent Office

Des. 233,567

Patented Nov. 5, 1974

233,567

CALENDAR HOLDER

Gordon Perry, Bayside, N.Y., assignor to Oxford
Pendafilex Corporation, Garden City, N.Y.

Filed Sept. 28, 1972, Ser. No. 295,981

Term of patent 14 years

Int. Cl. D19—03

U.S. Cl. D74—5 R

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a calendar holder showing my new design in transparent form;

FIG. 2 is a top plan view;

FIG. 3 is a front elevational view;

FIG. 4 is a left side elevational view;

FIG. 5 is a rear elevational view;

FIG. 6 is a bottom plan view;

FIG. 7 is a perspective view of the calendar holder shown in opaque form;

FIG. 8 is a top plan view thereof;

FIG. 9 is a front elevational view;

FIG. 10 is a left side elevational view;

FIG. 11 is a rear elevational view; and

FIG. 12 is a bottom plan view.

I claim:

The ornamental design for a calendar holder, as shown and described.
